UNITED STATES PATENT OFFICE

JENS N. MORTENSEN, OF BROOKLYN, NEW YORK, ASSIGNOR TO BOORUM & PEASE COMPANY, OF NEW YORK, N. Y., A CORPORATION OF NEW YORK

LOOSE-LEAF BINDER

Application filed October 11, 1928. Serial No. 311,844.

My invention relates to loose leaf extensible post binders of a type in which the locking means are independent of the posts on which the sheets are threaded.

5 The object of my invention is to provide such a loose leaf binder having a reduced number of parts, and which is economical to manufacture and easy to operate.

In the drawings

10 Figure 1 is a perspective view of the back of a binder made according to my invention, the two parts of the binder being separated;

Figure 2 is an end elevation of the back of 15 the same binder;

Figure 3 is a view similar to Figure 2, but in vertical section through the back taken on the line 3—3 of Figure 4;

Figure 4 is an elevation of the back of the 20 binder from the inside taken on the line 4—4 of Figure 2; portions of the binder and of the loose leaves or sheets contained therein being cut and broken away; while

Fig. 5 is a horizontal section through the 25 back of the binder taken on the line 5—5 of Figure 4.

The device comprises top and bottom binding bars 10 and 11, bearing means for retaining the perforated leaves or sheets 14. The 30 retaining means may be of any suitable kind. In the drawings they are of the alternating post type, that is to say, they comprise posts 12 carried by one binding bar alternated with posts 13 carried by the other binding bar. 35 The binder may be provided with covers 30, 31 of any desired type, which may be secured to the binding bars by any suitable means, as by rivets 32.

An adjustable back of the binder is formed 40 from two flanges 15, 16 mounted on and forming back portions for the binding bars 10 and 11 respectively. These flanges cover the back edges of the sheets and telescope with 45 each other. To keep the flanges in register with each other the ends 17 of the flange 16 of the lower bar 11 are bent around the ends 18 of the upper flange 15 as shown in Figure 1. The ends 18 of the upper flange are 50 crimped over upon themselves to provide

better guiding surfaces between the two parts.

The novel means for locking the two binding bars together includes vertical slots 19 in the upper flange having notches 20 therein and catches on the lower flange moving in the slots. The slots 19 are open at the free edge of the flange to permit separation of the top and bottom bars. There are two slots 19 in the upper flange and the notches 20 are 60 in the edges of the slots adjacent the nearest end of the flange. The two cooperating catches on the lower flange include a stud 21 adapted to engage and be retained by the notches 20, each stud being mounted on the 65 inner end of a pin 23 carried on the outer face of the lower flange 16. Each stud projects through a slot 22 in the flange 16 into 70 line with the notches 20.

When the two parts of the binder are 75 mutually engaged, as shown in Figure 4, spiral springs 24 wound on the pins 23 and secured under the heads 25 on the outer ends of the pins, each exert pressure which holds the stud in engagement with a notch 20, thus securing the two parts of the binder together.

To release the clamp, the operator presses simultaneously upon the heads 25 of the two 80 spring pins. This pushes the studs 21 toward the center of the binder and out of engagement with the notches 20, whereupon the two parts of the binder may be moved relatively to each other. They may be entirely separated, as shown in Figure 1, or the flange 15 may merely be raised or lowered slightly 85 in the grooves 17 of the flange 16, until each stud 21 is opposite a higher or a lower notch 20. Then on releasing the pressure upon the heads of the pins, the springs 24 force the studs 21 apart back into engagement with notches 20, thus fastening the two parts of the binder together again.

Other arrangements of the notches and consequently of the stud-operating means, within the scope of the invention, will occur to those skilled in the art.

The spring pin 23 may be attached to the flange 16 in any suitable manner, as by the stop 26, riveted to the flange.

The spring pins 23 may be covered by the 100

housing 27, which may conveniently be formed of a channel iron, as shown in Figure 3. In the form illustrated in the drawings, this channel iron is provided with a top flange 28 which is flush with the top of the flange 16 of the bottom bar, and need be no longer than is necessary to house the hinge pin. The lower flange 29 of the housing, is made long enough to underlie the bottom bar 11, and may be attached thereto by the same means 32 which attach the cover 31 to the bottom bar. If desired the web of the channel iron 27 may be made slightly longer than its flanges and may be bent at 33 to close the housing, as shown in Figure 2.

The spring pins, of course protrude through slots in 33, and extend far enough beyond the housing to allow them to be pressed inwardly by the fingers of the operator.

The housing protects the working parts of the device, presents an attractive appearance and gives a smooth surface.

If desired the top bar 10, may be provided with spring strip 34 (Figs. 1 and 4) to aid in compressing the sheets carried in the binder. The spring strip may be secured to the binder by any suitable means, as by one of the rivets which secures the cover to the top bar.

The binder of my invention provides an extremely economical structure doing away with the making and assembling of numerous parts heretofore used to give the expanding element.

I claim:

1. In a loose leaf post binder, a flanged binding bar, the flange being slotted adjacent each end, and the edge of each slot nearest the end of the flange being notched, in combination with a second flanged binding bar, movable studs carried by the flange of the second bar cooperating with the notches in the flange of the first bar, and stud-operating means on said second flange comprising a pin carrying each stud and a spiral spring surrounding each pin to press the stud away from the center of the binder to lock the binder; said pins being adapted to be pressed inwardly from the ends of the binder by the operator to unlock the binder.

2. In a loose leaf post binder a pair of binding bars, each having a back portion, the back portion of one binding bar being slotted and the slot being open at one end and having a notched edge, in combination with a spring-pressed locking stud on the back portion of the other binding bar, cooperating with the notched edge of the first binding bar.

3. In a loose leaf post binder a pair of binding bars, each having a back portion, the back portion of one binding bar being slotted and the slot being open at one end and having a notched edge, in combination with a spring-

pressed locking stud on the back portion of the other binding bar, cooperating with the notched edge of the first binding bar, the ends of the back portion of one bar being bent to receive and guide the ends of the back portion of the other.

In testimony whereof I have signed my name to this specification.

JENS N. MORTENSEN.
